UNITED STATES PATENT OFFICE.

LEE DE FOREST, OF NEW YORK, N. Y., ASSIGNOR TO DE FOREST PHONOFILM CORPORATION, A CORPORATION OF DELAWARE.

TALKING MOVING-PICTURE MACHINE.

Application filed December 7, 1923. Serial No. 679,260.

This invention relates to an attachment for moving picture machines or devices constructed in accordance therewith for producing or reproducing talking moving pictures, and has for its principal object the provision of instrumentalities or devices used in connection therewith which are simple in structure, efficient in operation and economical of manufacture.

10 A further object of the invention is to provide simple parts especially adaptable for use in connection with the talking or sound reproduction portion of a talking moving picture machine which may be simply adjusted and which permits ready accessibility and removal for replacement, cleaning, etc.

20 A further object of the invention is to provide a simple but efficient slit construction for a projector attachment and one which will permit a quick and permanent adjustment as to its size but which will at the same time likewise permit a sudden increase in size for cleaning purposes.

25 A further object of the invention is to provide a removable block which supports a presser bar.

30 A further object of the invention is to provide an attachment for standard motion picture machines which is simple in structure and self-contained and which will permit the use of such machines as a talking motion picture machine.

35 Further objects of the invention will appear more fully hereinafter.

35 The invention consists substantially in the construction, combination, location and relative arrangement of parts, all as will be more fully hereinafter set forth as shown in the accompanying drawings and finally pointed 40 out in the appended claims.

Referring to the drawings:

Figure 1 is a front view of a projector attachment embodying my invention.

Fig. 2 is a bottom plan view of the same.

45 Fig. 3 is a vertical, sectional view of the removable presser foot block.

Fig. 4 is a sectional view taken on the line 4-4, Fig. 3, looking in the direction of the arrows.

50 Fig. 5 is a face view of the slit-carrying plate with the slit devices and face plate removed.

Fig. 6 is a rear view of the same.

55 Fig. 7 is a rear view of the slit plate and slit former.

Fig. 8 is a sectional view taken on the line 8-8, Fig. 3, looking in the direction of the arrows.

Fig. 9 is a horizontal, sectional view of the arrangement shown in Fig. 3.

60 Fig. 10 is a fragmentary, detail view partially in section, showing the locking mechanism employed for locking the removable presser foot lock in place.

Fig. 11 is an enlarged, complete plan view 65 of the assembled structure.

Fig. 12 is a view in side elevation thereof.

The same part is designated by the same reference numeral wherever it occurs throughout the several views.

70 It is among the special purposes of my present invention to provide an attachment for motion picture machines which may be used in connection therewith to convert the same into a talking moving picture machine such as is generally described in my co-pending application Serial No. 635,334, filed April 28, 1923. This present invention, however, is directed to the details of structure of the attachment per se and to novel and important features thereof.

75 The invention is utilized with a film containing the sound record photographically obtained thereon, and the photographic sound record is utilized to control an electric circuit whereby the variations in the electrical circuit are re-converted into sound waves. The attachment is arranged at a suitable position with respect to the remainder of the machine, for example, as illustrated in my co-pending application above-identified, so that the film passes therethrough between a constant source of light and a photo-electric cell which is adapted to be included in an electric circuit to control the current flowing therethrough by and in accordance with the amount of light permitted to pass through the film, depending upon the sound record thereon.

80 Reference numeral 1 designates the attachment which consists essentially of a supporting frame 1 which serves to support the various instrumentalities which constitute the complete assembly. It also affords means to connect the attachment in any suitable manner, for example, to the top and bottom pieces 2 of the motion picture machine. The frame 1 supports, by means of suitable brackets 5, a platform 6 preferably of insulating material upon which is located an ammeter 7 85

and a rheostat 8 for controlling the same. The platform 6 likewise supports a switch block 9 and knife switch 10 for controlling the circuit of the ammeter and rheostat which in turn controls a light source enclosed in the light case 11 which extends through an orifice in the side wall of the frame 1 and directs the light therefrom through light tube 12, through light hole 13 (see Fig. 6) in the light slit assembly generally designated in Fig. 1 at 14. The opposite side of the frame 1 is provided with an aligned orifice in which is supported the end of the photo-electric cell 15. On either side of the slit assembly 14 is located a roller 16 suitably secured to the bottom of the frame 1 for rotation. The diameter of the rollers at their ends is larger than at the centers thereof and such diameters extend beyond the front surface of the slit assembly so as to afford free passage of the film thereby and at the same time confine the contact between the film and the roller to the marginal edge thereof. The rollers 16 are rotatably secured in any suitable way to the bottom of the frame 1, for example, by means of the screw studs 17 on which the rollers are rotatably mounted.

I will now describe the slit assembly with particular reference to Figs. 3 to 7. This consists of a plate 20 positioned between the rollers 16 and suitably, permanently secured to the bottom of the frame 1 in any manner, for example, by means of screws 21 extending through the bottom of the frame. This plate, the rear face of which is shown in Fig. 6, has, in the back thereof, and near its top, a circular depression 22 in which the end of the light tube 12 adjustably extends. It also has a restricted or light orifice 13 positioned at the approximate center of the circular chamber 22 extending through the plate. An air duct 23 is likewise provided through the plate 20 and connected to a nipple 24 extending through the bottom of the body 1 for the purpose to be hereinafter described. This air duct communicates with the circular chamber 22. The plate also supports a member 25 for rotation with respect thereto at a point in horizontal alignment to the center of the light orifice 13. This member is rotated by means of a lever 26 which extends beyond the rear face of the plate. The member 25 carries a pin 27 positioned off center with respect thereto whereby rotation of the member 25 secures a cam movement for the pin 27. The pin 27 projects through the front face of plate 20, as clearly shown in Fig. 5. A thumb adjustment screw 28 extends through the top of the plate 20 and is adapted to bear against the member 25 to prevent the movement thereof accidentally or through jar after an adjustment of the slit which the cam lever 26 controls, as will be hereinafter described, has been effected.

65 The next member of the slit assembly con-

sists of what I will term the slit plate, the rear view of which is shown in Fig. 7 and the front view of which is shown in Fig. 4, the central, vertical, sectional view being shown in Fig. 3. The rear of this plate, which is numbered 30, is provided with pins 31 adapted to seat in depressions 32 in the face of the plate 20 to ensure proper positioning. It is also provided with holes 33 therethrough to permit the same to be affixed to the front face of plate 20, for example, by means of screws 34. The slit plate 30 is grooved as at 35, the width of the groove being substantially the same as the width of the picture exposure of the film which passes therethrough. At the top of the grooved portion a narrow slot 36 is provided and extends half way across the width thereof. This slot is provided with beveled top and bottom edges 37 in the back face of the plate and a beveled side edge 38 at the approximate vertical center, of the plate. A removable slot forming member 39 formed of cooperating beveled edges and a flat surface is adapted to fit into the beveled recess of the plate 30. This member has a vertical groove 40 at one end thereof and a beveled end 41 at the other end thereof to cooperate with the sharp beveled edge 38 to form a slot 42. It will be obvious that by moving the member 39 in its recess the slot 42 may be adjusted to any desirable size, and due to the fact that the slot is formed by beveled edges, the same may be very accurately controlled. The cam pin 27 fits into the groove 40 of the member 39 so that upon rotation of the lever 26 the pin will move upwardly or outwardly, as the case may be, in the groove 40, moving the slit forming member 39 in one direction or the other, depending upon the direction of rotation of the lever 105 26. Guide plates 47, 48, are provided at the top and bottom of the plate 30 and overhanging the same so as to, in effect, form a slot through which the film passes. One of the plates, preferably the lower plate 48 as 110 shown, is yieldingly pressed upward by means of the spring 49.

I will now describe the presser foot block assembly particularly as illustrated in Figs. 3, 8, 9 and 10. This consists essentially of a block member 50 which is provided at its rear face with a circular slot 51 in which is positioned a sleeve 52, a spring 53 being positioned between the inner recess of the slot and the end of the sleeve 52 to normally force the same outwardly. Limit of movement of the sleeve is effected by means of a pin 54 secured to the sleeve 52 and projecting through an elongated hole 55 in the block 50. The block 50 carried at its surface top and bottom flanges 56 and 57, to form a recess portion 58 therebetween. The bottom flange 57 has horizontal lugs 59 and 60, which lugs are adapted to slide in the grooves of positioning flanges 61 and 62, respectively, which are suit-

ably secured to the body 1 in any manner, for example, by means of screws 63. The recess 59 is provided with a limiting center block 64 which limits the presser foot device 65 which 5 is supported by top and bottom pins 66, the ends of which are mounted in an elongated slot 67 of the flanges 56 and 57 and normally held forward by spring 68. This arrangement allows a yielding limited movement of 10 the presser foot assembly.

The guide flange 61 is provided with a space 70 formed between two projections 71 and 72 thereof, so that the lugs 59 may fit therebetween and be moved forwardly into 15 the position shown best in Fig. 9. The guide flange 62 carries a locking pawl member 75, the tooth 76 of which is adapted to engage the tooth 77 carried on the lug 60 of the presser foot block so that when the presser 20 foot block is placed in position it is locked there. To assemble the presser foot block, the compressible sleeve 52 is depressed flush with the rear surface of the block and the block positioned in the guide flanges 61 and 25 62 and moved forwardly until the dog 76 locks the same in position, the spring 53 pushing the sleeve 52 into flush contact with the side wall 2 of the frame 1. To further lock the presser foot block in position a rotatable lug 80 pivotally mounted as at 81 on 30 side 2 of the frame 1, is moved downwardly in position so that the foot 83 thereof bears 35 on the sleeve 52, as clearly shown in Figs. 8 and 12. The nipple 24, previously referred to, is provided for connection to a source of air pressure for cleaning the slot 42 if, as and when desired, without interfering with the assembly.

The side wall 2 of the frame 1 has hinged 40 at its end a gate or door 90 provided with a window 91 and a handle 92 to facilitate the opening of the door. This window permits a view of the assembly even when in operation, while at the same time protecting the 45 same against accumulation of dust, dirt or the like, and, together with the top and bottom of the camera and the back of the body 1, effectively encloses the apparatus in a chamber which may be looked into and to 50 which ready access may be had.

It will be seen from the foregoing that I have provided an exceedingly simple but highly efficient slit assembly and arrangement for a talking moving picture attachment for motion picture cameras and one wherein simplicity in structure, minimum of parts and ease of operation and control and disassembly are featured.

It is obvious that many modifications and 60 changes in details will readily occur to those skilled in the art without departing from the spirit and scope of my invention as defined in the claims, but having now set forth the objects and nature of my invention, and having shown and described a structure embody-

ing the principles thereof, what I claim as new and useful and of my own invention and desire to secure by Letters Patent is:

1. In a light slit assembly for a sound picture attachment, a supporting plate with 70 an orifice therethrough, a light slit plate positioned in front of said supporting plate and formed with a slot therethrough extending to the area of said orifice, and a slidable slit forming member mounted in said slot. 75

2. In a light slit assembly for a sound picture attachment, a supporting plate with 80 an orifice therethrough, a light slit plate positioned in front of said supporting plate and formed with a slot therethrough extending to the area of said orifice, a slidable slit forming member mounted in said slot, and means for moving said member in said slot to adjust the size of the slit formed thereby. 85

3. In a light slit assembly for a sound picture attachment, a supporting plate with 90 an orifice therethrough, a light slit plate positioned in front of said supporting plate and formed with a slot therethrough extending to the area of said orifice, a slidable slit forming member mounted in said slot, means for moving said member in said slot to adjust the size of the slit formed thereby, a plate, a 95 movable member carried by said plate to cooperate therewith from a light slit, and means for moving said member to vary the size of said slit. 100

4. In a light slit assembly for a sound picture attachment, a supporting plate with 105 an orifice therethrough, a light slit plate supported by said supporting plate and formed with a bevel edged slot therethrough extending to the area of said orifice, and a beveled edged slit forming member slidably mounted in said slot. 110

5. In a light slit assembly for a sound picture attachment, a supporting plate with 115 an orifice therethrough, a light slit plate supported by said supporting plate and formed with a bevel edged slot therethrough extending to the area of said orifice, a beveled edged slit forming member slidably mounted in said slot, and means for moving said member in said slot to adjust the size of the slit formed thereby. 120

6. In a light slit assembly for a sound picture attachment, a supporting plate with 125 an orifice therethrough, a light slit plate supported by said supporting plate and formed with a bevel edged slot therethrough extending to the area of said orifice, a beveled edged slit forming member slidably mounted in said slot, means for moving said member in said slot to adjust the size of the slit formed thereby, a plate, a movable member carried by said plate to cooperate therewith from a light slit, and means for moving said member to vary the size of said slit. 130

7. In a sound picture attachment, and in combination with a light slit device, of a

- yieldable presser foot device associated with said light slit device, and means for removing said presser foot device out of association with said light slit device.
5. 8. In a sound picture attachment, and in combination with a light slit device, of a yieldable presser foot device associated with said light slit device, means for removing said presser foot device out of association with 55
10 said light slit device, and a presser foot yieldably carried by said presser foot device.
9. A presser foot device comprising a supporting block having an orifice extending therethrough, a presser foot yieldingly supported on one face thereof, and in front of 60
15 said orifice.
10. A presser foot device comprising a supporting block having an orifice extending therethrough, a presser foot yieldingly supported on one face thereof, and in front of 65
20 said orifice, and a telescoping sleeve surrounding said orifice and yieldingly projecting from said block at the opposite face thereof.
- 25 11. In a sound picture attachment for picture machines, a supporting body, a light slit device carried thereby, a presser foot device associated with said light slit device and removably carried by said body.
- 30 12. In a sound picture attachment for picture machines, a supporting body, a light slit device carried thereby, a presser foot device associated with said light slit device and slidably carried by said body.
- 35 13. In a sound picture attachment for picture machines, a supporting body, a light slit device carried thereby, a presser foot device associated with said light slit device and slidably carried by said body, and means 70
40 for locking said presser foot device in associated position with respect to said light slit device.
- 45 14. In a sound picture attachment for picture machines, a supporting body, a light slit device carried thereby, a presser foot device associated with said light slit device and slidably carried by said body, means for locking said presser foot device in associated position with respect to said light slit device, and 75
50 independent means for holding said presser foot device in position on said supporting body.
- 55 15. In a sound picture attachment for motion picture machines, and in combination 80
60 with a supporting body, a light chamber and a light sensitive cell supported by said body at opposite ends thereof, a light slit device and a cooperative presser foot device also supported by said body and positioned between said light chamber and said cell, and light tubes extending from said light slit device and said presser foot device to said light chamber and said cell respectively.
- 65 16. In a sound picture attachment for motion picture machines, and in combination with a supporting body, a light chamber and a light sensitive cell supported by said body at opposite ends thereof, a light slit device and a cooperative presser foot device also supported by said body and positioned between said light chamber and said cell, light tubes extending from said light slit device and said presser foot device to said light chamber and said cell respectively, and means 75
70 for removing said presser foot device.
- 75 17. In a sound picture attachment for motion picture machines, and in combination with a supporting body, a light chamber and a light sensitive cell supported by said body at opposite ends thereof, a light slit device and a cooperative presser foot device also supported by said body and positioned between said light chamber and said cell, light tubes extending from said light slit device and said presser foot device to said light chamber and said cell respectively, and means 80
85 for sliding said presser foot device out of cooperative position with respect to said light slit device.
- 85 18. In a sound picture attachment for motion picture machines, and in combination with a supporting body, a light chamber and a light sensitive cell supported by said body at opposite ends thereof, a light slit device and a cooperative presser foot device also supported by said body and positioned between 90
95 said light chamber and said cell, light tubes extending from said light slit device and said presser foot device to said light chamber and said cell respectively, means carried by said body for locking said presser foot device in cooperative position with respect to said light slit device, and independent means also carried by said body for holding said presser foot device in assembled position on said body.
- 100 105 In testimony whereof I have hereunto set my hand on this 28th day of Nov., A. D. 1923.
- LEE DE FOREST.
